UNITED STATES PATENT OFFICE.

THEODORE HINRICHES, OF BALTIMORE, MARYLAND.

ADVERTISING MEDIUM.

SPECIFICATION forming part of Letters Patent No. 364,588, dated June 7, 1887.

Application filed March 16, 1887. Serial No. 231,126. (No model.)

To all whom it may concern:

Be it known that I, THEODORE HINRICHES, a citizen of the United States, residing at Baltimore city, State of Maryland, have invented 5 certain new and useful Improvements in Advertising Mediums, of which the following is a full, clear, and exact description, reference being had to the accompanying drawings, forming part of this specification, in which—
10 Figure 1 represents an exterior elevation of my improvement, showing a portion of the same in section. Fig. 2 is a plan of one of the sections, showing one of the perforated tube-holding plates.

15 My invention relates especially to show-globes and similar articles used by druggists as recognized signs of their profession; and it consists in the peculiar constructions and combinations of devices which I shall hereinafter 20 fully describe and claim.

To enable others skilled in the art to which my invention appertains, I will now describe its construction and indicate the manner in which the same is carried.

25 In the said drawings, A and B represent, respectively, the lower and upper sections of a frame adapted to support the various parts of my device. These sections are made of any suitable material—such as spun metal—and 30 may be of any appropriate design and configuration and ornamented or embellished in any suitable manner to constitute an attractive medium for displaying the occupation or profession of the owner.

35 The lower section, A, is provided with a weighted base, *a*, to give a firm support to the device and to obviate the danger of the same toppling over, and the upper section is designed to have its top surmounted by a suitable ornament, the said ornament having a 40 tube or passage, *b*, through which the heated air passes from the interior of the frame, as I will hereinafter indicate.

Each of the sections A and B is provided 45 with a plate or diaphragm, C and D, respectively, and the lower section, A, has a second plate, E, which is located below and contiguous to the plate C, as shown in Fig. 1, these plates C, D, and E being held together and 50 uniting the sections by suitable tie-rods, *c*, and securing-nuts *d*. The plates C and D are per-

forated with an annular or other series of openings, *e*, (see Fig. 2,) through which pass the ends of suitable transparent tubes, *F*, of colored glass or containing colored liquids. The 55 lower closed ends of said tubes pass through the perforations in the plate C and rest upon the contiguous plate, E, while their upper ends, which are open, extend slightly above the plate D, and receive rubber or other stoppers, which prevents the evaporation of the liquids within the tubes. In addition to the 60 perforations *e* the plates are provided with openings *e'*, which not only lessen the weight of said plates, but also furnish means for the 65 escape of heated air within the frame.

The tubes *F*, as before stated, may be constructed of any transparent material, although I prefer to use glass, and may be of round, square, octagonal, or other form, and so mounted 70 between the plates that they may be readily removed in case of breakage or when it may be desired to modify or change the existing combinations of colors to vary the effect.

Through the center of the lower section, A, 75 passes a gas-pipe, *g*, which may be attached to the supply-pipe leading from the main, and on top of said pipe *g* is screwed or fitted a burner, *G*, preferably of the form shown in Fig. 1.

By experimenting with several forms of burners I have found that a burner having a small round opening, *m*, is best adapted for lighting up the space between the annular series of tubes, as it produces a thin elongated 85 flame, which illuminates the tubes and produces a beautiful effect, the flame being protected by a shade or chimney, which conducts the heated air to the passage or tube *b* in the upper section, B, from whence it escapes into 90 the room.

It is obvious that instead of using gas as the illuminating agent I may employ an electric light or a common oil-lamp, the result in either case being the same.

95 The upper section, B, of the frame is preferably divided at *n*, so that the upper portion becomes a cover, which is removable to facilitate the filling or the insertion and removal of the tubes and for lighting the centrally-disposed burner.

In operating my device, the cover is removed

and the tubes filled with the colored liquids, (care being taken to leave a small space between the liquid and stopper to accommodate the expansion of the former,) the gas is lighted 5 and the cover replaced.

I am thus enabled to provide a comparatively inexpensive and compact device and one which is especially attractive, as the light reflected through the colored tubes produces 10 many varied and beautiful effects.

In connection with the frame and different-colored tubes I employ a motor, M, of any approved construction, and connect the same by gearing with the lower plate, E, in such 15 manner that a rotary movement is imparted to the plates, thereby beautifying the effect of the transparent tubes and presenting to the eye an ever-changing combination of brilliant colors.

20 Small anti-friction rollers *r* are let into the bottom of the plate E, and bear upon a contiguous flange or track, thereby reducing the friction caused by the rotary movement of the plate.

25 Having thus described my invention, what I claim as new, and desire to secure by Letters Patent, is—

1. An improved show-globe for druggists, comprising an upper and lower section united together, and each having a perforated plate, a 30 series of closed glass tubes passing through said plate, a second plate carried by the lower section and mounted on a suitable track, and a motor in the lower section connected with said plate and rotating the series of tubes and 35 plates, substantially as described.

2. The section A, having the perforated plate C, the plate E, arranged contiguous thereto and supported on an annular track, and an upper divided section having a perforated 40 plate, D, and passage or tube *b*, in combination with a series of transparent liquid-containing tubes passing through said perforated plates and provided with elastic stoppers, tie-rods, and securing-nuts for uniting the sections, and a light within the center of the frame and the series of tubes, substantially as herein described.

THEODORE HINRICHs.
